UNITED STATES PATENT OFFICE

LEE J. BLACK, OF BEAUMONT, TEXAS

LOCKING DEVICE FOR DRIVE BUSHINGS

Application filed April 26, 1929. Serial No. 358,414.

This invention relates to grief stem drive bushings and more particularly to a means for locking the grief stem drive bushing to the intermediate bushing or inner table section or rotary well drilling apparatus.

An important object of the invention is to provide an efficient latching means for connecting the grief stem drive bushing and the intermediate bushings of rotary well drilling apparatus which is of such character that it may be readily released to permit independent removal of the drive bushing, or may be employed in lifting the intermediate bushing or a portion thereof as set forth in my copending application Serial No. 358,416, filed Apr. 26, 1929.

A further object of the invention is the provision in apparatus of this character of a construction such that over-flow or leakage water or slush may be directed through the table and passed to the bore of the well about the bushing.

A still further object of the invention is to provide an apparatus of this character which may be readily and cheaply manufactured, which will be durable and efficient in service, and a general improvement in the art.

These and other objects I attain by the construction shown in the accompanying drawings wherein for the purpose of illustration I have shown a preferred embodiment of my invention and wherein:—

Figure 1 is a plan view showing a grief stem drive bushing and intermediate bushing connected by a lock constructed in accordance with my invention;

Figure 2 is a side elevation partially in section thereof;

Figure 3 is a section on line 3—3 of Figure 2;

Figure 4 is a view of the grief stem drive bushing removed;

Figure 5 is a section on line 5—5 of Figure 4;

Figure 6 is a fragmentary sectional view through the upper portion of the intermediate bushing.

Referring now more particularly to the drawing, the numeral 10 generally designates the inner section of an intermediate

drive bushing which may conveniently be the inner section of a drive bushing of the character illustrated in my co-pending application above identified.

These intermediate bushings are formed with a polygonal opening 11 for the reception of a polygonal shoulder formed upon the grief stem drive bushing, which is generally designated at 12, and this opening terminates in a downwardly tapering bore indicated at 13. In accordance with my invention, this bore at a point immediately below the polygonal opening is formed with a circumferential groove designated at 14, this groove being preferably V-shaped.

The grief stem drive bushing is formed intermediate its ends with a polygonal section 15 adapted to engage within and fit in the polygonal opening 11 of the intermediate bushing 10. The lower portion of this bushing is constructed to fit the opening 13 and from a point immediately beneath the polygonal section 15 to a point adjacent to, but spaced from its lower end, is provided with vertically extending grooves 16, which serve to reduce the weight thereof and to produce substantially radially extending ribs 17.

Such bushings are usually formed in two sections and in accordance with my invention each section is provided with an opening 18 through the polygonal portion 15 immediately above the groove 16. The lower end of this opening communicates with the groove 16, while the upper end thereof communicates with a groove 19 formed in the upper portion of the bushing section.

Between the upper ends of the rib 17 which are associated with the opening 18, I pivot as at 20, a lever 21 which extends upwardly through the opening 18 and has at its lower end an angular shoulder 22 to engage in the groove 14 of the intermediate bushing when the lever is swung outwardly. A spring 24 constantly urges this lever outwardly to provide for this engagement.

The shoulder 22 is disposed above the lower end of the lever and when engaged with the wall of groove 14 is disposed outwardly of the pivot 20, with the result that any pressure

tending to lift the bushing while the levers 21 are in their outer position will tend to cause the levers to swing outwardly to a greater extent, and thus tend to increase the grip 5 exercised by the levers upon the intermediate bushing. It will, however, be obvious that by simply engaging the upper ends of levers 21 and swinging them inwardly so that they extend into the recess 19 these levers will be 10 freed from the grooves with the result that the drive bushing may be readily removed in order that splash water and slush collecting about the drive bushing may be carried away without passing over the top of the rotary table, of which the structure just described is a part. I connect the lower ends 15 of the groove 16, which are associated with the openings 18, with the lower ends of the drive bushing by grooves 25, with the result 20 that any water which tends to collect about the drive bushing and pass downwardly through the space between the drive bushing and the intermediate bushing will pass to the groove 14 and from this groove find its way through 25 the groove 16 and ports 25 to the bottom of the drive bushing from which it may pass downwardly into the well.

Since the construction employed is obviously capable of a very considerable range of 30 change and modification without in any manner departing from the spirit of the invention, I accordingly do not limit myself to such specific structure except as hereinafter claimed.

35 I claim :-

1. In means for locking a grief stem drive bushing to intermediate bushings, and in combination with a grief stem drive bushing and an intermediate bushing having nesting engagement with one another and held against relative rotation when in engagement, the intermediate bushing having a horizontal groove formed therein, levers pivoted to said grief stem drive bushing and having parts to engage in the groove of the intermediate bushing when the levers are moved in one direction, and springs substantially urging said levers in said direction.

2. In means for locking a grief stem drive bushing to intermediate bushings, and in combination with a grief stem drive bushing and an intermediate bushing having nesting engagement with one another and held against relative rotation when in engagement, the intermediate bushing having a horizontal groove formed therein, levers pivoted to said grief stem drive bushing and having parts to engage in the groove of the intermediate bushing when the levers are moved in one direction, and springs substantially urging said levers in said direction, the grief stem drive bushing being provided with grooves in which the lower ends of said levers are pivoted and having openings formed 15 through the upper portions thereof through

which said levers are directed, the lower ends of the grooves being connected to the lower end of the bushing by ports.

3. In means for locking a grief stem drive bushing to intermediate bushings, and in combination with a grief stem drive bushing and an intermediate bushing having nesting engagement with one another and held against relative rotation when in engagement, the intermediate bushing having a horizontal groove formed therein, levers pivoted to said grief stem drive bushing and having parts to engage in the groove of the intermediate bushing when the levers are moved in one direction, and springs substantially urging said levers in said direction, the pivots of said levers lying inwardly of and below the groove engaging portions thereof.

4. In means for locking a grief stem drive bushing to intermediate bushings, and in combination with a grief stem drive bushing and an intermediate bushing having nesting engagement with one another and held against relative rotation when in engagement, the intermediate bushing having a horizontal groove formed therein, levers pivoted to said grief stem drive bushing and having parts to engage in the groove of the intermediate bushing when the levers are moved in one direction and springs substantially urging said levers in said direction, the grief stem drive bushing being provided with grooves in which the lower ends of said levers are pivoted and having openings formed through the upper portions thereof through which said levers are directed, the lower ends of the grooves being connected to the lower end of the bushing by ports, the pivots of said levers lying inwardly of and below the groove engaging portions thereof.

5. In combination, an intermediate bushing having a polygonal opening formed therein and having a tapered bore leading downwardly from the opening, the wall of the bore immediately below the lower end of the opening having a circumferential V-shaped groove, a grief stem drive bushing having its lower end adapted to fit within the tapered bore and having intermediate its ends a polygonal shoulder for engagement in the opening of the intermediate bushing, the wall of the drive bushing beneath said polygonal portion having grooves, the polygonal portion having openings aligning with said grooves, levers pivoted within said grooves and extending through the openings of the polygonal portions, shoulders on said levers adapted to engage in the groove of the intermediate bushing when the upper ends of the levers are outwardly disposed, and springs for constantly urging the upper ends of the levers outwardly.

6. In combination, an intermediate bushing having a polygonal opening formed

therein and having a tapered bore leading downwardly from the opening, the wall of the bore immediately below the lowered end of the opening having a circumferential V-shaped groove, a grief stem drive bushing having its lower end adapted to fit within the tapered bore and having intermediate its ends a polygonal shoulder for engagement in the opening of the intermediate bushing, the wall of the drive bushing beneath said polygonal portion having grooves, the polygonal portion having openings aligning with said grooves, levers pivoted within said grooves and extending through the openings of the polygonal portions, shoulders on said levers adapted to engage in the groove of the intermediate bushing when the upper ends of the levers are outwardly disposed, and springs for constantly urging the upper ends of the levers outwardly, the pivots of the levers lying inwardly of and below the groove engaging portions thereof.

In testimony whereof I affix my signature.
LEE J. BLACK.
